UNITED STATES PATENT OFFICE.

BOYD M. SCOTT, OF COALPORT, PENNSYLVANIA, ADMINISTRATOR OF,
WALTER W. O'MALLEY, DECEASED.

ELECTRICAL TRACTION DEVICE.

SPECIFICATION forming part of Letters Patent No. 722,255, dated March 10, 1903.

Application filed April 3, 1902. Serial No. 101,297. (No model.)

To all whom it may concern:

Be it known that WALTER W. O'MALLEY, late a citizen of the United States, and a resident of Pocahontas, Virginia, but now deceased, did invent certain new and useful Improvements in Electrical Traction Devices, of which the following is a specification.

This invention relates to electrical traction devices and certain coöperating accessories especially fitting such apparatus for use in moving mining-cars and trucks from one portion of the mine to another, the object being to enable the motor to be directed back and forth not only through the main drift of the tunnel, but also through the laterals thereof without making it necessary to supply such main tunnel and all of the laterals with a trolley-wire.

A further object of the invention is to provide reliably efficient means for supplying the electric motor with an actuating-current of electricity even in the absence of a trolley-wire and a return-ground for each of the lateral drifts or auxiliary tunnels, it only being necessary to provide a simple carrying-truck of the usual or any preferred construction.

Other objects and advantages will be hereinafter made clearly apparent, reference being had to the accompanying drawings, in which—

Figure 1 is a side elevation of the electric motor complete, also showing the coöperating storing or winding drum and controlling mechanism therefor. Fig. 2 is a top plan view of the motor complete. Fig. 3 is a front elevation of the motor and carrying-trucks. Fig. 4 is a detail showing an end elevation of the compensating winding-drum and also the brushes or terminals of the electric wires. Fig. 5 is a detail showing means employed to accurately control the compensating winding-drum.

For convenience of reference to the various details of the invention and coöperating elements numerals will be employed, of which 1 indicates the carrying wheels or trucks, of the usual or any preferred construction, while 2 designates the frame proper of the machine properly mounted upon said carrying-wheels and designed to carry the electric motor 3, of any preferred style, said motor being placed

in coöperative relationship with the driving-axle 4, as by means of the gear-wheels 5 and 6, as clearly shown in Fig. 2.

It will be understood that since it is not always practical to supply a properly-mounted trolley-wire above the track in all of the laterals or drifts of a mine it becomes desirable and important to provide other means for actuating the motor, if one is employed on said laterals or branches, and therefore a suitable electric cable is provided, combining in itself a lead and return wire, the said cable being indicated in the drawings as 7, one end of which is properly connected to the drum 8, having the head-sections 9 and 10, the former head-section being also provided with the contact-plate 11. The inner end of said electric cable 7, it will be obvious, should be connected to the drum by a suitable binding-screw, (not shown,) which will place said end of the cable in connection with the contact-plate 11, and since said contact-plate is properly connected to the brushes 12 and 13 and said brushes are in turn connected to the motor-actuating cable 14 by means of the branches 15 and 16 said motor will be actuated by the current, as will be obvious. It will be further apparent that a suitable controller 17 will form a connecting-link in the motor-cable 14, whereby the current may be readily wholly cut off or graduated, as desired, by means of the devices 18 and 19, as is common. The outer or free end of the cable 7 is provided with the branches 20 and 21, each having a suitable hook-terminal 22 and 23, respectively, whereby the wires represented by said branches 20 and 21 may be placed, respectively, in engagement or co-operation with the trolley-wire 24 and the ground-rail 25 when it is desired that the motor shall leave the main track which is supplied with the trolley-wire and proceed throughout the length of one of the laterals or drifts unsupplied with a trolley-wire, as is common. When the motor is thus placed in communication with the current, as indicated in Fig. 1, the motor will be actuated and may be driven forward toward the inner end of one of the laterals or drifts represented by the track-rails 26, and the cable 7 will be paid off by the drum 8 until the end of the drift

shall have been reached, said cable 7 being sustained by means of the grooved wheel 27, which is loosely mounted upon the shaft 28, supported by the standards 29. The wheel 27 being thus loosely mounted upon the shaft is left free to play between the standards 29, and thus compensate for the lateral strain or pull upon the cable 7. When the motor has proceeded the required distance toward the inner end of the drift or lateral tunnel and it is desired to return, the drum 8 will be automatically rotated by means of the compensating driving-wheel 30, which is secured to the shaft 31, upon which the drum 8 is rotatably mounted.

The drum 8 is provided with suitable bearings in the standards 32, and the driving-wheel 30 is held reliably in engagement with the contiguous truck-wheel by means of the compensating blocks 34 and the controlling-springs 35, said parts being suitably mounted in said standards 32, as clearly shown in the drawings. The shaft 31, therefore, is so mounted that it may be readily raised by the lever 36, so as to bring the wheel 30 out of engagement with the contiguous truck-wheel 1, the said controlling-lever 36 being connected to the shaft 31 by means of the link 33. The said lever 36 is connected, as shown in Fig. 1, to a contiguous part of the frame 2, while the free end thereof is provided with the controlling-handle 37. The free end of the lever 36 is bent to occupy a plane oblique with respect to the vertical plane of the standard 38, said standard comprising an inverted-U-shaped bar having one side thereof provided upon its inner edge with a rack-bar 39, adapted to engage the lower edge of the lever 36, and it is therefore obvious by raising the free end of the lever the driving-wheel 30 may be lifted out of contact with the contiguous truck-wheel 1, thereby leaving the drum to be freely unwound or rotated manually or by the simple act of driving the motor forward. Upon the return trip, however, of the motor the free end of the lever is lowered, so as to bring the wheel 30 in contact with the truck-wheel, when the drum will be rotated with sufficient speed to compensate for the travel of the motor, and thereby wind the cable upon the drum, so that the same will be all taken up out of the way of the motor. By the appliance thus provided or the equivalent thereof the motor may be freely directed back and forth over the track without any care on the part of the operator being directed to the cable 7, inasmuch as said cable will be stored and unwound automatically as required.

In Fig. 5 is illustrated the preferred means which may be employed to more reliably compensate for the winding and unwinding of the cable as it is stored or paid out incident to use, inasmuch as it will be observed that the truck-wheel 1 may be provided upon its outer edge with the extension or flange 40, having a plurality of apertures 41, designed to coöperate with the flange 42, carried upon the

outer edge or side of the driving-wheel 30, said flange 42 being provided with a plurality of lugs or teeth 43, designed to take into the apertures 41, provided in the flange 40. Since the diameters of the flanges 40 and 42 are identical in extent and the diameter of the winding-drum 8 formed accordingly, the rotation of the carrying-truck wheel 1 will insure that the drum 8 will be rotated so as to properly pay off and wind up the cable 7 as required incident to use.

It will be understood that various substitutes and equivalents may be employed in materializing this invention without departing from the spirit or scope thereof, and it is therefore desired to comprehend in this application all equivalents. The carrying-frame may also be provided with the usual trolley-pole 44, whereby the current may be directed from the trolley-wire 24, as is common. When, however, the motor is to be employed upon laterals unprovided with a trolley-wire, the cable 7 will be employed as hereinbefore specified. By the employment of this motor and compensating actuating-cable it is possible to avoid the use of mules or other animals now commonly employed to draw the cars from the laterals onto the main track.

The invention having thus been fully set forth, what is claimed is—

1. The herein-described traction device comprising suitable frame and carrying-truck, combined with a motor operatively connected to said truck, a cable-carrying drum rotatably mounted upon the said frame and operatively connected with the motor, a compensating cable connected to said drum and thus indirectly placed in communication with said motor, a controller for said motor, a compensating driving-wheel having a shaft mounted in movable bearings, a lever pivotally mounted upon the truck and a link connecting said lever with the shaft of the compensating wheel, all substantially as and for the purpose specified.

2. In a device of the character described, the combination with a carrying-truck and a motor operatively connected therewith, of a cable-carrying drum rotatably mounted upon the truck and operatively connected with said motor, a compensating wheel mounted on a shaft mounted in a movable bearing, a pivoted lever and a link connecting the same with said movable shaft, a compensating cable connected to said drum and thus indirectly placed in communication with said motor, a controller forming a connecting-link in said motor-cable and graduating devices for coöperation therewith.

3. In a device of the character described, the combination with the carrying-truck and the motor operatively connected therewith, of the drum, the driving-wheel, compensating blocks and springs therefor, the drum-shaft, a lever for bringing the driving-wheel out of engagement with the contiguous engagement with the truck-wheel, said lever

being mounted upon the frame and having its free end bent obliquely to the ordinary plane of the standard, said standard having an inverted-U-shaped bar provided upon one edge with rack-teeth adapted to engage the lower edge of said lever and a link connecting said lever with the shaft of the drum, all substantially as and for the purpose specified.

In witness whereof I, as administrator as above set forth, hereunto sign my name, in the presence of two witnesses, at Coalport, Pennsylvania, on this 7th day of March, 1902.

BOYD M. SCOTT.
